UNITED STATES PATENT OFFICE.

FRANK J. BARNARD, OF SEATTLE, WASHINGTON, ASSIGNOR OF TWO-THIRDS
TO JOHN CHARLES MOORE AND JOHN DETWILER ATKINSON, OF SAME
PLACE.

MAGNETIC SEPARATOR.

SPECIFICATION forming part of Letters Patent No. 560,184, dated May 19, 1896.

Application filed September 10, 1895. Serial No. 562,108. (No model.)

To all whom it may concern:

Be it known that I, FRANK J. BARNARD, a citizen of the United States, residing at Seattle, in the county of King and State of Washington, have invented certain new and useful Improvements in Magnetic Separators, of which the following is a specification.

My invention relates to a device for separating magnetic particles or substances from mixed masses of magnetic and non-magnetic particles by the action of a magnet or magnetized plate located over a sluice through which the mixed mass is passed.

My invention consists of a series of magnets or a magnetized plate located above a non-magnetic base or conveyer-plate, which is reciprocated by any suitable means over a sluice; and my invention further consists of certain details of construction that will be hereinafter described, and pointed out in the claims.

In order that my invention may be fully understood, I will proceed to describe the same with reference to the accompanying drawing, which shows a perspective view of my device.

In the said drawing, A represents a sluice, through which water carries the mass of magnetic and non-magnetic particles, and B represents a series of magnets which may be either permanent or electromagnets, or, if desired, a magnetized plate may be employed. These magnets are located in a suitable non-magnetic casing C, provided with the perforations D for permitting a free circulation of air through the casing, and the said casing C is secured to the frame E. This frame E, as will be seen, is adjustably secured to the frame F. This is to permit the adjustments of the magnets nearer to or away from or at an angle to the conveyer G, according to the strength of attraction desired.

H represents tracks located under the casing C and passing over the sluice A, and I represents a conveyer mounted on rollers J

and traveling on the tracks. This conveyer I is formed of copper or other non-magnetic substances and is provided on its under face, preferably, with serrations or strips, although, if preferred, the under face may be smooth. 50

K represents a crank mounted in suitable journals, and L a pulley secured onto the axle thereof, by which the crank is turned, and any suitable means (not shown) may be employed for driving the crank. M represents 55 a pitman-rod connecting the conveyer to the crank.

The operation of my device is as follows: The magnetic and non-magnetic particles are carried through the sluice by the water passing therethrough, and as it comes under the magnets the magnetic particles are attracted onto the conveyer-plate and as it is reciprocated over the sluice the particles are conveyed to either side of the sluice, where, after moving out of the magnetic field, they drop by their own weight. 60

Having thus described my invention, the following is what I claim as new therein and desire to secure by Letters Patent:

1. In a magnetic separator, the combination of a sluice, a magnet located over said sluice, a conveyer-plate formed of non-magnetic material located under said magnets and over the sluice, and suitable means in connection with the plate for reciprocating it, substantially as shown and described. 70

2. In a magnetic separator the combination of a sluice, a magnet located over said sluice, and a conveyer-plate formed of non-magnetic material located under said magnet and over the sluice, strips or serrations of non-magnetic material located on said plate, and suitable means in connection with the plate for reciprocating it over the sluice, substantially as shown and described. 75 80 85

FRANK J. BARNARD.
